UNITED STATES PATENT OFFICE

117,343

DESIGN FOR A RIBBON

John D. Huizing, New York, N. Y.

Application November 10, 1938, Serial No. 81,016

Term of patent 3½ years

To all whom it may concern:

Be it known that I, John D. Huizing, a citizen of the United States of America, residing in New York city, in the Borough of Manhattan, county and State of New York, have invented a new, original, and ornamental Design for a Ribbon, of which the following is a specification, reference being had to the accompanying drawing, forming part thereof, wherein

Fig. 1 is a plan view of a ribbon showing my new design;

Figs. 2 and 3 are views on reduced scale of opposite faces of the fabric.

I claim:

The ornamental design for a ribbon, substantially as shown and described.

JOHN D. HUIZING.
